MULTIPLE DIRECTION SEWING MACHINE

Leo Roseman, Newark, N. J., assignor to Prime
Machine Co. Inc., Newark, N. J., a corporation
of New Jersey

Application October 30, 1934, Serial No. 750,655

23 Claims. (Cl. 112—204)

This invention relates to a sewing machine of the general type disclosed and claimed in my copending application Serial No. 744,642, filed September 19, 1934.

5 A prime object of the invention is to provide a novel and improved sewing machine whereby the direction of feed of the work can be changed at will approximately instantaneously at sharp angles without manual manipulation or turning 10 of the work and without interruption of the operation of the machine to form in one continuous operation a plurality of lines of stitches extending in different directions and meeting at angles.

15 The invention is especially suitable for sewing two seams of a garment at angles to each other, or sewing a label to a garment with a continuous line of stitches extending around the marginal portions of the label, although many other uses 20 of the invention will occur to those skilled in the art.

In accordance with preferred embodiment of the invention, I may utilize a sewing machine which includes a drive shaft, a stitch forming mechanism, and a work feed dog which is operatively connected to the drive shaft by connections certain of which move the dog horizontally back and forth while the other actuates the dog vertically up and down, the dog being raised 25 and moved horizontally in one direction in engagement with the work to move the latter and then being lowered away from the work and moved horizontally in the other direction to its initial position, so that the work is moved horizontally relatively to the stitch forming mechanism. In known sewing machines of this general character the feed dog is movable horizontally in only two directly opposite directions so as to move the work in one direction, but in my 30 copending application Serial No. 736,806, I have shown means for also periodically varying the operation of the feed dog to reverse the work feeding movement thereof. My present invention contemplates a 35 machine of this character wherein the operation of the feed dog can be varied at will to reverse the feed of the work, or to cause the work to be fed successively in directions at right angles to each other, or to cause the work to be fed diagonally.

40 More particularly the invention contemplates novel and improved means for horizontally actuating the feed dog back and forth in opposite directions, other means for operating the dog back and forth in directions at right angles to

the first-mentioned directions, and means for causing a composite or simultaneous movement of the first two mentioned means for actuating the feed dog back and forth in directions diagonal to the first two named directions, whereby, 5 for example a garter may be stitched to a corset by continuous lines of stitches arranged in the form of a rectangle and other lines of stitches disposed diagonally of the rectangle, in one continuous operation.

10 A further object is to provide a multiple direction sewing machine which shall embody two needles in the stitch forming mechanism and novel and improved work feeding mechanism whereby two parallel lines of stitches may be 15 formed in one direction and a line of double stitches can be formed at the ends of said parallel lines and disposed at right angles thereto without turning the work and without breaking 20 or loose threads or loss of stitches.

25 The invention further has in view the cooperation with all of said means for horizontally moving the dog, of a common means for operating the dog vertically or up and down to engage and disengage the work.

30 Other objects of the invention are to provide a machine of the character described which shall be relatively simple, reliable, durable and inexpensive in construction and operation, and to obtain other advantages and results as will be 35 brought out by the following description.

35 Referring to the accompanying drawings in which corresponding and like parts are designated throughout the several views by the same reference characters,

Figure 1 is a side elevation of a sewing machine embodying my invention.

Figure 35 is a transverse vertical sectional view on the line 35—35 of Figure 34.

45 Figure 36 is a horizontal sectional view on the line 36—36 of Figure 29, portions being omitted for clearness of illustration.

Figure 37 is a schematic plan view of the mechanism for adjusting the follower roller relative to the cam to reverse the direction of horizontal movement of the feed dog, according to the form of the invention illustrated in Figures 1 to 8 inclusive.

50 Figure 38 is a similar view showing the same operation of the form of machine shown in Figures 29 to 36 inclusive.

Figures 39, 40 and 41 are fragmentary plan views of the cam and follower roller showing the adjustment of the follower roller in accordance with a form of the invention shown in Figures 55 60 29 to 36 inclusive and Figure 38.

Figure 42 is a schematic perspective view of the feed dog operating mechanism embodying the form of the invention shown in Figures 1 to 28 inclusive, portions being omitted.

65 Figure 43 is a perspective view of a line of stitches.

Figures 44 to 49 inclusive show the various steps in a cycle of movement of the feed dog for 70 feeding the work forwardly to form the line of stitches shown in Figure 43.

Figure 50 shows the beginning of a line of stitches formed on backward movement of the feed dog.

75 Figures 51 to 56 inclusive show the cycle of

movement of the feed dog during backward feeding thereof.

Figure 57 shows the position of the feed dog at the beginning of lateral feeding movement.

Figure 58 shows the beginning of a lateral line 5 of stitches.

Figures 59 to 62 inclusive show the cycle of movement of the feed dog during lateral feeding, in one direction.

Figure 63 shows a position of the feed dog at 10 reversal of the lateral feeding motion.

Figure 64 shows the beginning of a line of stitches on reverse lateral feeding.

Figures 65 to 67 inclusive show the cycle of movement of the feed dog during reversed lateral feeding.

Figure 68 shows a position of the feed dog at 20 the beginning of diagonal feeding movement.

Figure 69 shows a beginning of a diagonal line of stitches.

Figures 70 to 72 inclusive show the cycle of movement during a diagonal feeding.

Figure 73 shows the position of the feed dog at the beginning of forward longitudinal feeding after the diagonal feeding.

Figure 74 shows the beginning of a line of stitches during forward longitudinal feeding.

Figures 75 to 77 inclusive show the cycle of movement of the feed dog during the forward longitudinal feeding.

Figure 78 shows the position of the feed dog at the beginning of another diagonal feeding movement.

Figure 79 shows the first stitch in the line to be formed during such diagonal feeding movement.

Figures 80 to 82 inclusive show the cycle of movement of the feed dog during the diagonal feeding.

Figures 83 to 85 inclusive show the successive movements of the feed dog at the beginning of another forward longitudinal feeding.

Figure 86 shows a piece of work having lines of stitches formed during the various movements of the feed dog illustrated in Figures 44 to 45 inclusive.

Figure 87 shows two parallel lines of stitches each including angularly disposed portions formed by the use of two needles in the stitch forming mechanism.

Figure 88 is a similar view showing a double line of stitches formed by longitudinal feeding of the work through stitch forming mechanism including two needles.

Figure 89 is a like view showing two parallel lines of stitches formed by lateral movement of the work through a two needle stitch forming mechanism, and,

Figure 90 is a similar view showing two parallel lines of stitches and a double line of stitches at right angles thereto formed by successive longitudinal and lateral feeding movements of the work through a two needle stitch forming mechanism.

Specifically describing the illustrated form of the machine embodying my invention, the reference character A designates the bed plate of the machine which has the usual standard B thereon formed with a goose neck C at one end of which is mounted the needle bar D. The needle bar is driven in the usual way from the drive shaft E of the machine which is journaled in the standard B and goose neck C. With the needle bar and its needle, cooperates a bobbin mechanism F of the usual type, the needle bar and its operating devices and the bobbin and its

operating parts constituting a stitch forming mechanism.

The machine also includes work feeding mechanism for moving work through the stitch forming mechanism, that is, between the needle and the bobbin mechanism, and as shown, this work feed mechanism includes a feed dog 1 which is movable vertically and horizontally relative to the usual throat plate 2 in the bed of the machine, the dog being raised through the throat plate and moved horizontally in one direction in engagement with the work to move the latter and then being lowered away from the work and moved horizontally in the other direction to its initial position. Cooperating with the feed dog in the usual manner is a known type of presser foot G. The dog is operated from the drive shaft E of the machine and as shown is mounted on a link 3 one end of which is bifurcated at 4 and has a pin and slot connection 5 with a crank 6 on a counter shaft 7 journaled in the bed plate of the machine. The other end of the link 3 is pivotally connected at 8 to a crank 9 on another countershaft 10 journaled in the bed of the machine. The countershaft 7 is rotated alternately in opposite directions by a crank arm 11 connected to the shaft and having a bifurcated end 12 in which rotates a cam 13 mounted on a secondary drive shaft 14 which is journaled in the bed of the machine and is driven by the usual crank and pitman connection 15 from the drive shaft E. With this construction, the counter shaft 7 is rotated alternately in opposite directions so as to vertically raise and lower the said dog 1 through the throat plate 2 into and out of engagement with the work.

For actuating the feed dog horizontally back and forth to feed the work forwardly or backwardly, the counter shaft 10 is rotated alternately in opposite directions. As shown, the countershaft 10 has a pin 17 projecting laterally through a slot 18 in the bed plate of the machine, the end of the pin being arranged to enter a slot 20 in an actuating slide 21 so that the pin may have a hinged or pivotal connection with the slide and reciprocation of the slide will cause rotation of the shaft 10 alternately in opposite directions. As shown, the slide 21 is longitudinally reciprocable in a channel shaped guide 22 which is pivotally mounted at one end 23 on the bed of the machine.

One end of the slide 21 has a pin and slot connection 24 with one end of a lever 25 (see Figure 31) which is pivotally mounted at 26 on a horizontal axis on a bracket 27 secured upon the top of the bed A of the machine. Carried by the lever 25 is a follower roller 28 which is arranged in the cam groove 29 of a box cam 30 (see Figure 2). This cam 30 is mounted on an auxiliary shaft 31 that is journaled with its axis vertical in bearings 32 and 33 and which has a worm gear 34 which meshes with a worm 35 on the drive shaft E. The cam groove 29 has cam surfaces 36 which will be hereinafter described in detail, so that upon rotation of the cam through the gearing 34 and 35 the lever 25 will be oscillated about its pivot to reciprocate the actuating slide 21 and rotate the countershaft 10 when the pin 17 is in the notch 20 so as to actuate the feed dog 1 horizontally and vary the operation thereof.

For engaging and disengaging the actuating slide 21 with the pin 17, the guide channel 22 is oscillated about its pivot 23, and for this purpose I have shown a knee operated lever 37

pivotedly mounted intermediate its ends 38 on a bracket 39 secured to the front of the bed of the machine, one end of the lever 37 having a pin and slot connection 40 with a down-turned end of the guide channel and the other end of said lever having a knee rest 41 adjustably connected thereto to be engaged by the knee of the operator. By pressing the knee rest 41 to the right in Figure 1 of the drawings, the guide channel may be swung to the left to cause engagement of the pin 17 with the notch 20, and upon release of the knee rest, a tension spring 42 will swing the guide channel in the other direction to disengage the pin 17 from the notch 20.

For controlling the reciprocation of the actuating slide 21 the cam surfaces 36 of the cam 30 may be of any suitable configuration, for example, as shown in my copending applications Serial Nos. 736,806 and 744,642; but for simplicity in explanation, I have shown the cam surfaces as formed and arranged to produce a continuous line of stitches of equal length. The cam surfaces for each stitch are identical, so that I shall describe only one.

Referring to Figure 2 of the drawings, each cam surface includes a dwell 43 which when engaged by the follower roller 28 actuates the slide 21 so that the feed dog is at the beginning of its forward feed movement in engagement with the work as shown in Figure 6. In this position of the feed dog the shaft 7 has raised the feed dog into engagement with the work and holds it there during horizontal movement of the feed dog to the right in Figure 6. This horizontal movement is caused by an inclined surface 44 on the cam which causes the slide to be operated and move the feed dog to the end of its horizontal feeding movement, i. e. at the extreme right of the opening 2 in the throat-plate in Figure 6. When the feed dog reaches this position, the cam 30 has rotated to bring the follower roller 28 into engagement with another dwell 45 which interrupts horizontal movement of the feed dog while the shaft 7 lowers the feed dog away from the work. Thereupon the roller 28 is engaged by another inclined surface 46 which moves the feed dog backwardly or to the left in Figure 6 to the beginning of its forward work feeding movement. The next dwell 43 then engages the follower roller to interrupt horizontal movement of the feed dog while the shaft 7 raises the feed dog into engagement with the work at the beginning of its forward feeding horizontal movement, whereupon the continued rotation of the cam 30 brings the next inclined surface 44 into contact with the roller to cause another horizontal feeding movement of the feed dog. This cycle is then repeated throughout the rotation of the cam, one stitch being formed during each horizontal feeding movement of the feed dog, as usual.

In accordance with the invention, the direction of feeding movement of the feed dog may be reversed at will, and as shown in Figures 1 to 6 inclusive, this reversing movement is effected by manipulation of the worm 35 on the shaft E. The worm 35 has a key or feather and spline connection with the shaft E so as to move longitudinally of the shaft, and has a circumferentially grooved collar 47 in which rides a follower roller 48 on a pin 49 connected to a reversing slide 50 reciprocable in a guide bracket 51 on the top of the goose-neck of the machine.

The reversing slide is reciprocated by an operating bar 52 slidably mounted in the bracket 51 in a direction at right angles to the plane of reciprocation of the reversing slide 50. The operating bar has a cam slot 53 which engages a pin 54 on the reversing slide so that upon movement of the operating slide in opposite directions, the reversing slide is reciprocated in opposite directions respectively. Any suitable 10 manual or automatic means may be utilized for moving the operating slide, but I have shown a foot lever 55 connected by a chain or cord 56 to one end of the operating slide for moving the slide in one direction, a tension spring 57 being 15 provided for moving the slide in the other direction upon release of the foot lever. If desired, a handle 58 may be provided on the operating slide for actuating it in both directions.

The ratio of the movements of the various 20 parts is such that when the reversing slide 50 is moved in either direction, the worm 35 is slid on the shaft E a distance sufficient to rotate the cam 30 in one direction or the other relative to the follower roller 28 a distance adequate to 25 cause a reversal of movement of the feed dog. This manipulation or adjustment of the cam is schematically illustrated in Figures 9 to 11 inclusive. Assuming that in Figures 9 and 10 the cam is rotated in the direction of the arrows and 30 the follower roller 28 has moved from the position of Figure 9 to the position of Figure 10 so as to have completed a forward feeding movement of the feed dog, operation of the reversing slide 50 to the right in Figures 2, 7 and 8 will 35 cause the cam to be moved in the opposite direction as indicated by the arrow in Figure 11 so that the roller and cam will be returned to the same relation as shown in Figure 9. This will result in a movement of the actuating slide 40 and feed dog backwardly or in a direction opposite to the movement effected during operation of the parts from the position shown in Figure 9 to the position shown in Figure 10. Therefore, upon resumption of normal rotation 45 of the cam 30 in the direction of the arrows shown in Figure 9, the feed dog will feed the work backwardly. In other words, the dog will engage the work while it is moving from right to left of Figure 6 instead of while it is moving 50 from left to right. This reversal of movement of the feed dog may be effected at any time and in any position of the feed dog. When this reversing movement of the feed dog takes place while the shaft 7 is moving the feed dog downwardly away from the work, no stitches will be 55 formed during the reversal, but when the reversal is made while the feed dog is in engagement with the work, a stitch will be produced on top of the next preceding stitch. Obviously 60 movement of the operating slide 52 in opposite directions will cause reversals of movement of the feed dog in opposite directions respectively. Preferably, the feed dog has a knurled surface to 65 properly grip the work on movement in both directions.

In Figures 43 to 56 inclusive are illustrated the operations of the feed dog in forward feeding and reverse feeding of the work. Figure 43 shows a line of stitches formed upon forward 70 feeding of the work and Figure 44 shows the position of the feed dog I at the end of the forward feeding movement where the dog is in its upper position in engagement with the work W shown in dot and dash lines. Figure 45 shows the dog lowered away from the work as the 75

result of movement of the shaft 7 while Figure 46 shows the movement of the dog to the beginning of its forward feeding stroke but out of engagement with the work. Figure 47 shows the dog raised into engagement with the work 5 preparatory to beginning the next forward feed of the work and Figure 48 shows the dog at the end of the forward feeding. When the operating slide 52 is actuated to reverse the direction of the work with the feed dog in the position 10 shown in Figure 48, the dog is moved backwardly as shown in Figure 49. Thereupon the dog is lowered away from the work as shown in Figure 51 and then forwardly out of engagement with the work as shown in Figure 52 and then upwardly into engagement with the work as shown in Figure 53 and then backwardly in engagement with the work as shown in Figure 54 so as to move the work backwardly. This results in a reverse stitch designated by the reference character a in Figure 50. The dog is then moved downwardly away from the work after which this cycle of operations may be repeated to form a double row of stitches designated b in Figure 58.

The invention also contemplates a lateral or 20 sidewise feeding of the work, and for accomplishing this result, I have shown the feed dog laterally horizontally reciprocable. Specifically the crank 9 has a keyed or feather and spline connection with the shaft 10 so as to slide longitudinally of the shaft and is influenced in one direction by a compression spring 59 interposed between the crank and a collar 60 on the shaft. The crank has a lateral arm 61 to one end of which is connected a pull rod 62 the other end 30 of which is connected to one arm 63 of a bell crank lever 64 which is journaled on a stub shaft 65 on the bed of the machine. The other arm 66 of the bell crank has a head 67 to engage a notch 67' in the actuating slide 21. With this construction, when the actuating slide is connected to the head 67, reciprocation of the slide by the lever 28 will cause oscillation of the bell crank lever 64 and consequent horizontal lateral movement of the crank 9 and feed dog I (see Figure 40 45 42). This horizontal lateral movement of the feed dog has a timed relation to the vertical motion of the feed dog effected by the shaft 7, corresponding to the timed relation of the horizontal longitudinal movement of the feed dog 50 and said shaft 7. The bifurcated end 12 of the link 3 slides longitudinally of the pin 5 on the crank 6 to compensate for the sliding of the crank 9 longitudinally of the shaft 10.

Another feature of the invention is means for 55 causing feed of the work in directions which are composites of the longitudinal and lateral feeds, that is, a feed of the work diagonally. This diagonal feed may be effected by causing oscillation of the crank 9 and longitudinal movement thereof on the shaft 10 at the same time; in other words, by causing the actuating slide 21 to engage both the pin 17 and the head 67' of the bell crank lever 64. In order to so simultaneously connect the pin 17 and the head 67' to the 60 actuating slide I have shown the arm 66 of the bell crank lever as extensible. In Figures 12 to 16 inclusive, this arm 66 includes a main portion 69 on which is longitudinally slidably an extension portion 70 at the end of which is mounted 70 the head 67. A latch 71 is pivotally mounted on the extension 70 to cooperate with openings 72 in the main section 69 for holding the extension 70 in adjusted positions. When it is desired to 75 connect the head 67' to the actuating slide 21

simultaneously with the connection of the slide to the pin 17, the extension 70 is slid outwardly into the position shown in Figures 15 and 16, while when it is desirable to connect the actuating slide 21 to either the pin 17 or the head 67, separately, the extension 70 is slid inwardly into the position shown in Figures 12 and 14. When the extension is in this position, the actuating slide 21 may also be located in neutral position, that is, unconnected with either the pin 17 or the head 67 as shown in Figure 12. As shown, the head 67 and pin 17 are preferably located at opposite sides of the slide 21 to facilitate these operations.

15 In operation of the mechanism, when the actuating slide 21 is in neutral position as shown in Figure 12 the slide may be reciprocated by the lever 25 without any horizontal motion of the feed dog. To cause horizontal longitudinal motion of the feed dog, the actuating slide 21 is swung to the left as shown in Figure 13 to engage the pin 17, while when it is desired to cause simply lateral motion of the feed dog, the actuating slide is swung to the right as shown in Figure 14 to engage the head 67, while when diagonal motion of the feed dog is desired, the actuating slide is swung into engagement with the pin 17 after which the bell crank arm 66 is extended to engage the head 67 with the actuating slide, as shown in Figure 15.

Figure 17 is a schematic plan view of the feed dog operating mechanism with the parts in neutral position, while Figure 18 shows the parts in the position assumed for beginning longitudinal horizontal movement of the feed dog. Figures 19 and 20 show the actuation of the slide 21 and the feed dog 1 successively in opposite directions.

40 Figures 21 to 23 inclusive show the corresponding steps in the horizontal lateral reciprocation of the feed dog. Figure 24 shows the position of the parts preparatory to beginning diagonal horizontal actuation of the feed dog, while Figure 25 shows the completion of the adjustment of the parts for such diagonal lateral motion.

45 Figures 26 and 27 show the operation of the parts successively in opposite directions during diagonal actuation of the feed dog and Figure 28 shows the disconnection of the head 67 from the actuating slide.

With the feed dog moving horizontally either longitudinally, laterally or diagonally the dog may be caused to move in either of the other two 50 directions at the will of the operator. Furthermore, the feed dog may at will be caused to feed in either of opposite directions longitudinally, laterally or diagonally. In Figure 57 the feed dog is shown as having been changed from backward longitudinal feeding to lateral feeding, the dog being disengaged from the work at the beginning of lateral feeding of the work in the direction of the arrow. Figure 59 shows the dog raised into engagement with the work at the beginning of the feeding movement while Figure 61 shows a dog at the end of the feeding movement. Figure 62 shows the dog being lowered away from the work and Figure 63 shows it returned to the initial position shown in Figure 57. 55 With the dog moving in this manner, a lateral line of stitches c may be formed. In Figure 64 the direction of lateral movement of the dog is shown as changed so as to reverse the direction of feed of the work as indicated by the arrow, 60 the dog being disengaged from the work. Figure 65

ures 65 and 66 show the dog at the beginning and ending of its feeding movement respectively, while Figure 67 shows the dog lowered away from the work at the end of the feeding movement. This operation will result in a double line 5 of lateral stitches c' shown in Figure 64. Figure 68 illustrates a change in the movement of the dog from lateral feeding to diagonal feeding, the dog being shown out of engagement with the work. In Figure 70, the dog is shown as moved 10 out of engagement with the work to the beginning of its diagonal feeding motion while Figure 71 shows the dog raised into engagement with the work at the start of the feeding motion. Figure 72 shows the dog in engagement with the 15 work at the end of its feeding movement while Figure 73 shows the dog disengaged from the work. This cycle of operations will produce a diagonal line of stitches d. Between the positions shown in Figures 73 and 75 the direction of 20 movement of the dog has again been changed to forward longitudinal feeding, Figures 75 to 77 showing the cycle of operations of forward feeding from a line of stitches e. In Figure 78 the the position of the dog is shown as again changed to 25 feed diagonally in the direction opposite to that illustrated in Figures 70 to 72 inclusive so as to form a diagonal line of stitches f; Figures 80 to 30 inclusive show the steps in the cycle of movement of the dog. In Figure 83 the direction of 35 movement of the dog is again illustrated as longitudinally forward to form a stitch g, Figure 84 illustrates the end of the forward feed movement. In Figure 85 the dog is shown as stationary as when the machine is stopped. 35

All of the stitching hereinbefore described, is formed with a single needle, but the invention is of course susceptible of use in a two needle machine. Here two needles are used, parallel rows of stitching h and i may be formed as shown in Figures 87 and 89 or a row of double stitches k may be formed in one operation as shown in Figure 88. By feeding the work longitudinally parallel rows l of single stitches may be formed, and then by feeding the work laterally a row of double stitches m may be formed at right angles to the rows l. The stitching described is simply illustrative of the many different forms of stitching which may be accomplished with my machine, and it will be understood by those skilled in the art that the machine may be used for making various forms of stitches without departing from the spirit or scope of the invention. 45

50 It will be understood from the foregoing that the drive worm 35 in connection with the reversing slide 50 may be utilized for reversing the direction of movement of the feed dog when the dog is moved either longitudinally, laterally, or diagonally. 55

Instead of manipulating the worm 35 to reverse the direction of feeding movement of the feed dog, I may move the follower roller 28 relatively to the cam. A structure for accomplishing this result is shown in Figures 29 to 36 inclusive. In this form of the invention, the bracket 27 for supporting the lever 25 is slidably mounted in the bed plate of the machine, for example, the bracket may have a portion 75 projecting through a slot 76 in the bed of the machine with a cap plate 77 for holding the bracket against displacement, and the bracket may be slid on the bed plate by a hand lever 18 connected to a shaft 19 journaled in the bed of the machine and having a crank arm 80 which is connected by a 60 65 70 75 80 85 90 95 95

link 81 to the bracket. Obviously, by sliding the bracket laterally, the position of the follower roller 28 relative to the cam may be varied as shown in Figures 39 to 41 inclusive. This adjustment corresponding to that illustrated in Figures 9 to 11 inclusive for effecting reversal of the direction of movement of the feed dog.

To compensate for the sliding movement of the bracket, the pin and slide connection between the lever 25 and the actuating slot 21 must permit lateral movement of the lever relative to the slide, and as shown in Figure 34 the slot in the lever may be elongated as indicated at 83 to slide laterally of the pin or stud 84 on the actuating slide. The machine shown in Figures 29 to 36 otherwise operates in the same manner as the machine shown in Figures 1 to 6 inclusive.

Figures 37 and 38 are schematic comparative views of the two ways of causing relative adjustment of the cam and follower roller, Figure 37 showing the adjustment effected by movement of the worm 35 as shown in Figures 1 to 6 inclusive, while Figure 38 shows the adjustment effected by moving the bracket as shown in Figures 29 to 36 inclusive.

Instead of moving the follower roller 28 relative to cam 30 for reversing the feed, I may provide any suitable known type of reversing mechanism for simply reversing the direction of rotation of the cam.

While I have shown the cam 30 in the form of a box cam, it will be understood that a plain cam 82 may be utilized as shown in Figure 32. However, where a plain cam is used, a spring 35 10A must be provided for holding the follower roller in engagement with the cam (see Figure 3 of the drawings).

It will be understood that the invention is also susceptible of use in a sewing machine having a vibratory or oscillating needle bar.

While I have shown and described my invention as embodied in certain details of construction and as utilized for certain purposes, it should be understood that this is primarily for illustration of the principles of the invention, and that the machine may be embodied in other details of structure and used for other purposes without departing from the spirit or scope of the invention.

Having thus described my invention, what I claim is:

1. A sewing machine of the character described comprising a stitch forming mechanism, a work feed dog movable horizontally in either of two angularly disposed directions and a direction composite of said two directions, two means one for moving the feed dog selectively in each of said two angularly disposed directions, an actuating mechanism, and manually operable means for effecting at will simultaneous connections of said actuating mechanism to both of said first named two means to cause movement of said dog in said composite direction.

2. A sewing machine of the character described comprising a stitch forming mechanism, a work feed dog movable in either of two angularly disposed directions, an actuating mechanism, means for operatively connecting said actuating mechanism to said feed dog for horizontally longitudinally reciprocating said feed dog, and other means for operatively connecting said actuating mechanism to said feed dog for horizontally laterally reciprocating said feed dog, said actuating mechanism being capable of connection and disconnection to and from said two means selectively.

3. A sewing machine of the character described comprising a stitch forming mechanism, a work feed dog movable in either of two angularly disposed directions, an actuating mechanism, means for operatively connecting said actuating mechanism to said feed dog for horizontally longitudinally reciprocating said feed dog, and other means for operatively connecting said actuating mechanism to said feed dog for horizontally laterally reciprocating said feed dog, and means for causing connection and disconnection of said actuating means and either of said last named two means selectively.

4. A sewing machine of the character described comprising a stitch forming mechanism, a work feed dog movable in either of two angularly disposed directions, an actuating mechanism including a rotatable cam, a reciprocating slide and an operative connection therebetween, two means for operatively connecting said slide to said feed dog for horizontally reciprocating the dog longitudinally and laterally respectively, means for causing connection and disconnection of said slide and either of said last named two means selectively, and means operating in timed relation to said two means respectively for moving the feed dog alternately into and out of engagement with the work.

5. The machine set forth in claim 2 wherein said actuating mechanism is also capable of being connected to the last named two means simultaneously to cause reciprocation of said feed dog diagonally.

6. The machine set forth in claim 4 with the addition of means for permitting connection of said slide to said last named two means simultaneously to cause horizontal reciprocation of said feed dog diagonally.

7. The machine set forth in claim 1 with the addition of means for selectively reversing the movement of said feed dog.

8. The machine set forth in claim 2 with the addition of means for vertically reciprocating said feed dog in timed relation to said longitudinal and lateral reciprocations respectively to move the dog alternately into and out of engagement with the work to move the work in one of opposite directions, and means for varying the horizontal longitudinal and lateral movements of the dog selectively to reverse the direction of movement of the work.

9. In a machine of the character described a stitch forming mechanism, a work feed dog, means for moving said work feed dog vertically alternately into and out of engagement with the work, and means for reciprocating said dog horizontally laterally of the plane of vertical movement of said feed dog in timed relation to said vertical movement comprising a cam, a reciprocating slide and an operative connection therebetween, and means for operatively connecting said slide to said feed dog.

10. In a machine of the character described a stitch forming mechanism, a work feed dog, means for moving said work feed dog vertically alternately into and out of engagement with the work, and means for reciprocating said dog horizontally laterally of the plane of vertical movement of said feed dog in timed relation to said vertical movement, comprising a cam, a reciprocating slide and an operative connection therebetween, angularly disposed crank arms oscillatory about a common axis and operatively connected to said feed dog and said slide respectively.

11. In a machine of the character described

a stitch forming mechanism, a work feed dog, means for moving said work feed dog vertically alternately into and out of engagement with the work, a cam, a reciprocating slide and an operative connection therebetween, two means for operatively connecting said slide to said feed dog for horizontally reciprocating the feed dog longitudinally and laterally, in timed relation to said vertical movement, said two means having parts arranged at opposite sides of said slide to connect therewith and said slide being laterally movable selectively into engagement with either of said parts.

12. In a machine of the character described a stitch forming mechanism, a work feed dog, means for moving said work feed dog vertically alternately into and out of engagement with the work, actuating mechanism, two means for operatively connecting said actuating mechanism to said feed dog to reciprocate the latter horizontally and laterally respectively, in timed relation to said vertical movement, said two means each having a part arranged in spaced relation to the other and said actuating mechanism having an element laterally movable between said two parts to selectively connect with either thereof.

13. The machine set forth in claim 11 with the addition of means permitting connection of said element of the actuating mechanism to both of said two parts simultaneously.

14. In a machine of the character described, a drive shaft, a stitch forming mechanism, a work feed mechanism including a feed dog, means for vertically reciprocating said dog into and out of engagement with the work, a rotatable cam and an operative connection between it and said dog, said cam having surfaces to cause horizontal reciprocation of said dog in timed relation to said vertical reciprocation to feed the work, a worm on said drive shaft, a worm gear meshing therewith and connected to said cam, said worm being movable longitudinally of said drive shaft for momentarily changing the relation of said cam to said operative connection to vary the position of the feed dog to reverse the direction of horizontal movement thereof.

15. In a machine of the character described, a drive shaft, a stitch forming mechanism, a work feed mechanism including a feed dog, means for vertically reciprocating said dog into and out of engagement with the work, a cam and an operative connection between it and said dog, said cam having surfaces to cause horizontal reciprocation of said dog in timed relation to said vertical reciprocation to feed the work, a driving connection between said drive shaft and said cam, and means for momentarily varying the relation of said cam to its operative connection with said dog to vary the position of the feed dog to reverse the direction of horizontal movement thereof.

16. In a machine of the character described, a drive shaft, a stitch forming mechanism, a work feed mechanism including a feed dog, means for vertically reciprocating said feed dog into and out of engagement with the work, a cam, a follower therefor and an operative connection between said follower and said dog to cause horizontal reciprocation of said dog in timed relation to said vertical reciprocation to feed the work, a driving connection between said drive shaft and said cam, and means for momentarily moving said follower relatively to said

cam surface to change the position of said feed dog and reverse the direction of horizontal movement thereof.

17. In a machine of the character described, a drive shaft, a stitch forming mechanism, a work feed mechanism including a feed dog, means for vertically reciprocating said feed dog into and out of engagement with the work, a rotatable cam, a follower therefor and an operative connection between said follower and said dog to cause horizontal reciprocation of said dog in timed relation to said vertical reciprocation to feed the work, a driving connection between said drive shaft and said cam, and means for momentarily reversing the direction of rotation of the cam for reversing the direction of feed of the work.

18. A sewing machine of the character described comprising a stitch forming mechanism, a work feed dog movable horizontally in any one of a plurality of angularly disposed directions, mechanism including a common driving cam and a separate means for positively actuating said feed dog horizontally in each of two of said directions, means for reciprocating said dog vertically in timed relation to said horizontal movements, and means for selectively operatively connecting said driving cam to either of said separate means or simultaneously to both thereof to cause feeding of the work selectively in either of said two directions or in a direction composite of said two directions.

19. In a machine of the character described, a drive shaft, a stitch forming mechanism, a work feed mechanism, a cam, a follower therefor and an operative connection between said follower and said work feed mechanism to actuate the latter and feed the work to said stitch forming mechanism, a driving connection between said drive shaft and said cam, and means for selectively momentarily reversing the direction of movement of the cam to reverse the direction of feed of the work.

20. In a machine of the character described, a drive shaft, a stitch forming mechanism, a work feed mechanism, a cam, a follower therefor and an operative connection between said follower and said work feed mechanism to actuate the latter and feed the work to said stitch forming mechanism, a driving connection between said drive shaft and said cam, and means for selectively momentarily varying the relation of the cam to its connection with the work feed mechanism to reverse the direction of feed of work.

21. A sewing machine of the character described comprising a stitch forming mechanism, a work feed dog movable horizontally in any one of a plurality of angularly disposed directions, mechanism including a separate means and a common driving cam with common cam surfaces for positively actuating said feed dog horizontally in each of said directions, means for reciprocating said dog vertically in timed relation to said horizontal movements, a follower for said cam, and manually operable means for at will selectively operatively connecting said follower to either of said separate means to cause feeding of the work selectively in any of said directions.

22. A sewing machine of the character described comprising a stitch forming mechanism, a work feed dog movable horizontally in any one of a plurality of angularly disposed directions, mechanism including a separate means

and a common driving cam with common cam surfaces for positively actuating said feed dog horizontally in each of said directions, means for reciprocating said dog vertically in timed relation to said horizontal movements, a follower for said cam, and manually operable means for at will selectively operatively connecting said follower to either of said separate means to cause feeding of the work selectively in any of said directions, and means for selectively reversing movement of the work feed dog.

23. A sewing machine of the character de-

scribed comprising a stitch forming mechanism, a work feed dog movable horizontally in any one of a plurality of angularly disposed directions, means for positively actuating said feed dog in any of said directions, and means for selectively operatively connecting said actuating means to said feed dog to cause the feeding of work to said stitch forming mechanism selectively in any one of said directions, and means for selectively reversing movement of the work feed dog.
